(57) **CLAIM**

The ornamental design for a "television set", as shown and described.

DESCRIPTION

FIG. 1 is a top, front and right side perspective view of a television set according to my design;
FIG. 2 is a front elevational view thereof;
FIG. 3 is a rear elevational view thereof;
FIG. 4 is a top plan view thereof;
FIG. 5 is a bottom plan view thereof; and,
FIG. 6 is a left side elevational view thereof; the right side elevational view being a mirror-image thereof.
